(57) **CLAIM**

The ornamental design for a pair of cat ear headphones, as shown and described.

DESCRIPTION

FIG. 1 is a perspective view showing my design;
FIG. 2 is a front view showing my design;
FIG. 3 is a back view showing my design;
FIG. 4 is a left side view showing my design;
FIG. 5 is a right side view showing my design;
FIG. 6 is a top plan view showing my design; and,
FIG. 7 is a bottom plan view showing my design.
The broken lines depict environment that forms no part of
the claimed design.

1 Claim, 7 Drawing Sheets
